UNITED STATES PATENT OFFICE.

YORKE BURGESS, OF CHICAGO, ILLINOIS, ASSIGNOR TO THE BURGESS COMPANY, A CORPORATION OF ILLINOIS.

ENVELOPE.

1,420,470.

Specification of Letters Patent: Patented June 20, 1922.

Application filed December 13, 1920. Serial No. 430,243.

To all whom it may concern:

Be it known that I, YORKE BURGESS, a citizen of the United States, residing at Chicago, in the county of Cook and State of Illinois, have invented certain new and useful Improvements in Envelopes, of which the following is a specification.

This invention relates to improvements in envelopes, and has especial reference to double envelopes, adapted for carrying differently classified mail matter in the respective separated pockets.

Business houses in mailing catalogs to prospective customers find it expedient, many times, to accompany the catalog with a personal letter. If the two communications be mailed in a single sealed envelope, the postal charges are excessive and often prohibitive. If they are mailed under separate covers, the delay in transmission on the catalog, or the like, which is received so long after the receipt of the letter, will, in a great measure, cause the transaction to lose the beneficial and psychological effects that otherwise would obtain, by the simultaneous receipt and consideration of the two pieces of mail matter.

One of the objects of the present invention is to provide a double envelope, one for a catalog, or the like, and the other for a letter and to indicate the distinctive character of mail matter to be contained in each envelope, on the face of one of the composite envelopes, in a manner permissible by the postal authorities, and convenient for the user and the persons through whose hands the dual package passes.

Another object is to provide an envelope that will be inexpensive to manufacture; that will require but one address for both packages; one envelope provided with means for sealing, the other having an unsealed flap, to be tucked in, to retain the lower class mail matter therein.

Other, further and more specific objects of the invention will become readily apparent to persons skilled in the art, from a consideration of the following description when taken in conjunction with the drawings, wherein:—

Fig. 1 shows the address side and the regions within which to apply the stamps thereon for each envelope and contents.

Fig. 2 is a plan view of a formed sheet 55 of which the double envelope is to be made.

Fig. 3 shows the form after the first fold.

Fig. 4 shows the form after the second fold, with the envelope structure completed and ready for use.

Fig. 5 is a transverse section taken on line 5—5 of Fig. 1.

Fig. 6 is a similar view taken on line 6—6 of Fig. 1.

In all the views the same reference characters are employed to indicate similar parts. 65

The sheet of which the envelope is to be made may consist of paper, or other suitable substance, in the form substantially as shown in Fig. 2, in which there are three main sections 10, 11 and 12 that are designed to be 70 folded upon the dotted lines 13 and 14, respectively.

Section 10 is provided at one end with a flap 15 having glue 16 applied to one surface. The first operation is to fold the section 10 on line 13 and have it superposed above section 11, then the glued flap 17 is secured to the back or outside surface of section 10. This closes the bottom of the pocket intended for first class matter. Now, section 12 is folded over the top of section 10 80 and the glued side flap 18 is caused to adhere along the horizontal edge of section 11 and on its opposite or outside surface. After this has been done the flap 15 is folded over 85 and glued to the outside surface of one end of section 12. This closes the bottom end of the pocket intended for third or fourth class matter. This leaves the glued flap 19 to close the envelope to contain first class matter after the contents is placed therein and leaves the unglued, longer flap 20 open to be tucked in after inserting the catalog, or the like.

On the outside surface of section 12, in 95 the upper right hand corner, the position where the stamp is required to be placed, is printed the legend "Third or fourth class postage here," or similar instruction. Near the left hand bottom corner is outlined, as 100 at 21, the form of a first class letter, and in the right hand upper corner of this form, in the space to be covered by the postage stamp, is printed the legend "Letter postage here." The stamps, therefore, for the first 105 class matter and third or fourth class matter are placed on the same side of the double envelope. Above the space occupied by the outline 21 may be printed, for the convenience of the user, this legend "Third or 110

fourth class in this end (unsealed)." An elongated arrow 22 may point to the end referred to and within the region mentioned will be printed another legend "First 5 class in this end (sealed)," with an arrow 23 pointing to the end referred to. In the upper left hand corner of the outline 21 may be printed the address of the sender with instructions to the postmaster as to 10 the ultimate disposition of the package, in case of non-delivery.

It will, of course, be manifest to persons skilled in the art, that the flap 15 may be on the upper end of section 12, the flap 20 15 may be on the lower end of section 10, and the flap 18 on the outer edge of the section 10, instead of being placed as shown, without changing materially the structure described.

20 There is no visible evidence of the third or fourth class enclosure from the front view of the structure, except that it bears stamps that are located in the upper right hand corner. The sealed flap 19 appears 25 upon the face presented to the observer, but the flap 20, which is tucked in around the third and fourth class matter, is not visible, unless the envelope be reversed, on the back side of which there is no printing or other 30 indicia.

Having described my invention what I claim as new and desire to secure by Letters Patent, is:—

1. A double envelope made of a single 35 sheet having three connected, rectangular sections folded on two, spaced apart, parallel lines, one end section folded over the intermediate section, the other end section folded over the opposite folded end section and 40 joined to the latter at its folded edge thereby to form two open pockets; an outwardly folding flap to close the respective pockets at opposite ends; a flap at each open end to be subsequently closed; a space on one side of 45 the double structure containing directions for affixing the stamps for the differently classified mail matter, to be subsequently

covered by the stamps to be applied; indicia on said face of the envelope indicating the character of mail matter to be contained in 50 the respective envelopes and an outline indicating a smaller envelope with a return address within said outline and space for a mailing address therein.

2. A double pocket envelope made from 55 a single sheet having three rectangular sections folded on two parallel lines, one end section folded upon the intermediate section and the other end section folded upon the first end section; an end flap on the intermediate section and folded upon the outside of the first end section to form a pocket; a side flap on the other end section and folded upon the outside of the intermediate section to form a second pocket; two end flaps, one 60 on the intermediate section and one on the first end section and foldable upon the outside of the second end section to separately 65 close adjacent ends of the two pockets; and an end flap on the second end section to close 70 the opposite end of one pocket.

3. An envelope having two pockets for different class mail matter and made from a single sheet folded along two parallel lines to form one intermediate section and two 75 end sections, one end section folded upon the intermediate section and secured thereto along a transverse edge by an overlying flap of the intermediate section, the other end section folded upon the first end section and carrying a flap which is folded over a longitudinal edge of the intermediate section, the intermediate and first end sections having flaps at one end of the envelope which are 80 separately foldable in the same direction 85 over the corresponding end of the second end section to close both pockets at one end of the envelope and the second end section having an unsealed flap that can be tucked into the open end of the adjacent pocket. 90

In testimony whereof I hereunto subscribe my name.

YORKE BURGESS.
